UNITED STATES PATENT OFFICE.

JABEZ BATH, OF BROOKLYN, NEW YORK.

CALENDAR.

SPECIFICATION forming part of Letters Patent No. 247,000, dated September 13, 1881.

Application filed July 19, 1881. (No model.)

To all whom it may concern:

Be it known that I, JABEZ BATH, of Brooklyn, in the county of Kings and State of New York, have invented a new and Improved Calendar, of which the following is a full, clear, and exact description.

The object of my invention is to furnish a changeable and perpetual calendar of durable construction and in convenient form.

10 In the accompanying drawings, Figure 1 is a perspective view of a calendar constructed in accordance with this invention. Fig. 2 is a vertical section of the same on line $x x$ of Fig. 1; and Fig. 3 is a perspective view of one of the calendar-blocks.

15 Similar letters of reference indicate corresponding parts.

The supporting stand or frame may be of any suitable construction. As shown, it consists 20 of a base, A, and vertical portion B, provided with side strips, a , that form a recess for receiving the calendar-blocks and cards.

In the top of the frame is an oblong recess, covered on the front by a slotted slide, b , and 25 in this recess there are cubical blocks e , that are numbered on their faces. These are the year-blocks, and are to be arranged to show the year-number through the slot in the slide b . Next below the space for the year-blocks is a space that 30 receives the monthly cards d . A slide, e , in the side strip, a , allows for insertion and change of the cards as required.

Below the month-cards are the calendar-blocks f , which rest on the base A, and are retained in place by the slide-strips $g h$, which 35 extend through slots in the side strips, a , so as

to cover the blocks f at their upper and lower ends. The blocks f are oblong and four-sided, and are numbered on their faces to indicate the days of the month, so that when placed in proper 40 order they form a monthly calendar. Each block f has the same numbers on two or more of its sides, but differently placed to suit the different positions of the block from month to month. Each face is also numbered at the bottom, so that a table of directions can be used 45 to indicate the order in which they are to be placed. These numbers are covered by the slide h .

On the slide g are the names of the days of 50 the week, which completes the calendar. This slide h is retained in place by the slide e , before mentioned.

The numbers on the calendar-blocks $e f$ may be printed, stamped, or otherwise affixed, and 55 the month-cards d may be made of metal, cardboard, or any other suitable material. I do not limit myself in that respect. Neither do I confine myself to the described arrangement of slides for allowing insertion and removal of 60 the calendar-blocks.

Having thus described my invention, I claim as new and desire to secure by Letters Patent—

The combination of the blocks f , cards d , and frame B, provided with slides $e g h$, substantially as shown and described, to form a changeable calendar.

JABEZ BATH.
